UNITED STATES PATENT OFFICE.

ALBERT L. STOUT, OF MIDDLETOWN, KANSAS.

FLOOD-GATE.

SPECIFICATION forming part of Letters Patent No. 281,941, dated July 24, 1883.

Application filed March 2, 1883. (Model.)

To all whom it may concern:

Be it known that I, ALBERT L. STOUT, a citizen of the United States, residing at Middletown, in the county of Wilson and State of 5 Kansas, have invented a new and useful Flood-Gate, of which the following is a specification.

My invention is designed to obviate the necessity of giving personal attention to flood or water gates in time of freshets or rises in water-courses. It is automatic in principle, and will (being properly adjusted) open when the pressure of the rising water makes it necessary for the free passage thereof, and will close when the pressure of the water ceases, and at the 15 same time will answer the purpose of a fence.

In the accompanying drawings, forming a part of this specification, and on which like letters of reference indicate corresponding parts, Figure 1 represents a perspective view of my 20 improved flood-gate, showing the gates partially open, as viewed from the upper side or toward the head of the stream; and Fig. 2 represents a similar view of my gate as viewed from the lower side or toward the mouth of the 25 stream.

The letter A indicates the upper gate; B, the lower gate; C, the operating-rod; D, the left-hand post; E, the right-hand post; F, the right-hand post on which the gate A swings, and G 30 the left-hand post on which the gate B swings.

The letter H indicates the short operating-rod extending from the bottom of the posts F and G.

I indicates the longitudinal beam forming 35 the rear portion of the gate A, and J J the upright posts of the said gate. The letter K refers to the gage or pressure-board, which is adjustably secured to the gate A by means of the staples 5, which fit over the uprights J 40 and the pin 4, which extends through the horizontal beam I, the adjustment of the board be-

ing effected by withdrawing the pin 4 and elevating or lowering the gate until one of the upper or lower apertures formed therein registers with the said pin. Upright rods 1 serve 45 to connect the upper and lower horizontal beams of the gate B, the post G of which is provided with studs or trunnions 3, which play in the hinges 2.

The gage or pressure-board, indicated by the 50 letter K, is adjusted in the manner above described, so as to be raised or lowered according to the depth of water, presenting a broad smooth surface, against which the pressure of the water acts, whereby the gate is opened and 55 a free passage for the water thus provided. When the water subsides, the pressure thereof against the lower gate, B, closes it, and it in turn closes the upper gate through the medium of the rods C and H.

Having thus fully described my invention, what I claim as new, and desire to secure by Letters Patent, is—

1. The combination, in an automatic flood-gate, of the two gates hinged, respectively, to 60 posts located approximately opposite each other, one of said gates being provided with an adjustable pressure-board, with the operating-rod secured at its respective ends to said gates, substantially as shown and described.

2. The combination, in an automatic flood-gate, of the two gates hinged to separate posts, one of which is provided with an adjustable pressure-board and fastening devices for said board, with an operating-rod secured to the 75 hinged end of each of the gates, substantially as shown and described.

ALBERT L. STOUT.
